UNITED STATES PATENT OFFICE

HARVEY L. WHITLEY, OF FREMONT, NORTH CAROLINA

TELEPHONE LINEMAN'S TEST SET

Application filed October 25, 1932. Serial No. 639,514.

This invention relates to test sets of the type used by telephone linemen for testing the line wires and the invention consists in the provision of such a set wherein all the parts 5 may be readily placed within a single container, and the single container easily carried by the lineman.

The invention also comprehends the provision of a casing or receptacle for the necessary elements of the set, that is of comparatively simple construction, and which will accommodate the elements of the set in a compact manner and will further permit of an arrangement of the elements within the receptacle in a manner to permit ready access to any desired element or elements.

The invention together with its numerous objects and advantages will be best understood from a study of the following description taken in connection with the accompanying drawings wherein:

Figure 1 is a perspective view of the set illustrating the manner of using the same,

Figure 2 is a sectional view taken substantially on the line 2-2 of Figure 1.

Figure 3 is a sectional view taken substantially on the line 3-3 of Figure 2.

Referring more in detail to the drawings it will be seen that the set, in accordance 30 with the present invention includes the usual and conventional form of elements or equipment, namely the transmitter 1, receiver 2, head piece 3 for the receiver, switch 4, batteries 5, transformer 6, magneto 7, the latter 35 also including the usual gearing 8 and operating shaft 9, together with the wire 10 for the receiver 2, wire 11 for the transmitter 1, and the wiring 12 connecting the switch with the other electrical parts of the 40 set in addition to the wiring 13 that is provided with the clips 14 adapted to be engaged with the line wires 15 in the manner well known in the art and suggested in Figure 1.

When not in use, all the parts above mentioned are arranged within a casing or receptacle 16. The casing or receptacle 16 in accordance with the present invention comprises an outer casing or receptacle 17 of metal, and the casing 17 is closed at its bottom, 45 and is open at its top. For the top of the

casing 17 is provided a metallic lid or cover 18 hinged to the casing 17 as at 19.

There is provided for the receptacle 17 and its lid 18 a collapsible and easily removable lining which lining in the present instance is formed of wood although it may be formed of any other suitable material. The said lining comprises a main frame like part for the walls of the receptacle 17, and this part of the lining consists of a plurality of 55 blocks 20 adapted to be arranged within the casing 17 in the manner clearly shown in the drawings.

For securing the blocks or pieces 20 of the lining in assembled relation within the receptacle 17 I provide a plurality of bolts 20, there being preferably four of such bolts, and the latter extend through a pair of opposed blocks 20 and at one end have nuts 22 engaged therewith. As shown in Figure 70 3 the heads of the bolts are accommodated in sockets provided therefor in one of the said opposed members 20 while the nuts 22 are similarly accommodated by the other of said opposed lining members 20. 75

For the bottom of the receptacle or casing 17 there is also provided a lining block 23, while a lining block 24 is provided for the lid 18.

A partition block 25 of wood or other suitable material is hinged as at 25' to one of the lining blocks 20 above the uppermost bolt 21. On a relatively opposite block 20 there is provided an angle plate 26 for supporting the free end of the partition block 25. Carried by the free end of the partition block 25 is a bolt 27 and has its threaded end adapted to be screwed into an aperture in the flange of the angle plate 26 for securing the partition block 25 in its horizontal position, 90 that is in the position shown in Figure 2.

As shown, the batteries 5, transformer 6, and magneto 7 are all arranged within the casing 17 below the partition 25 and are assembled within the casing 17 in any appropriate manner, preferably in the manner shown. 95

The batteries 5, which battery may be of the ordinary flash light type are arranged in a suitable casing 28 provided at its top with 100

- a removable lid 29. Carried by the top 29 are the binding posts 30 usually provided for electrically connecting the battery in circuit, and these posts 30 are suitably insulated 5 from the cap 29 through the medium of an insulation block 31 arranged internally of the cap, and washers 32 of insulating material fitted within the apertures provided in the cap 29 for accommodating the posts 30. 10 In the bottom of the casing 28 there is also provided a block 33 of insulating material which is suitably provided to accommodate the electrical connection 34 between the lowermost set of batteries 5 as shown in Figure 3. 15 The casing 28 is securely anchored within the casing through the medium of a single bolt 35 that extends downwardly of the casing through the top 29, and which has its lower end threaded into a socket suitably provided in the bottom lining block 23. 20 As shown in Figure 2 the switch 4 is mounted on the underside of the said partition block 25, and that lining block 20 to which the partition block 25 is hinged, is provided with a suitable recess 36 for accommodating one end of one of the contacts of the switch 4. Said one partition block 20 is also provided with a vertical aperture extending upwardly from the recess 36 for accommodating a plunger 37 that is normally urged upwardly through the medium of a spring 38 provided within a socket formed in the upper end of said lining block 20, and engaging the head of the plunger 37. In this 25 connection it will be noted that the referred to lining block 20 is arranged against the inner face of that wall of the casing 17 to which the lid 18 is hingedly connected. The block 24 of the lid 18 adjacent the hinge 19 is provided with a screw or other suitable element 39 forming an abutment that is adapted to engage the head of the plunger 30 when the lid is moved to a closed position for moving the plunger 30 downwardly thus 30 flexing the said one contact of the switch 4 downwardly to open said switch. Manifestly, when the parts are arranged entirely within the casing 17 and the lid 18 thereof is in closed position, the switch 4 will be in open 35 position.

As shown in Figure 3, the casing 17 above the partition 25 is large enough to accommodate the transmitter 1, head piece 3, receiver 22, and the wire 13 when the set is not in use.

For limiting swinging movement of the lid 18 to an open position there is provided a suitable length of chain or other flexible element 40 that is secured at one end to the block 24, and at its other end to the partition 25. When the parts or equipment of the set are fully arranged within the casing 17, they are located in a manner clearly suggested in Figure 3. A suitable clasp such as is indicated

generally at 40 is provided for securing the lid 18 in a closed position.

For operating the magneto 7, a crank may be readily applied to the shaft 9 of the magneto through alined openings 43 provided in one side of the casing 17, and an adjacent lining block 20. For the openings 43 there is provided a pivoted closure or door 44.

On one side thereof the casing 17 has secured thereto an attaching plate 45 equipped with a ring 46. On a relatively opposite side, the casing is also provided with a second plate 47, and a ring 48 engaged with the plate 47. A strap 49 of suitable length is provided at each of its ends 50, 51 with a buckle as shown. The end 51 of the strap is provided with an adjustable loop in the manner shown, and this loop is engaged with the eye 46. The end 50 is also provided with a loop, and at the loop end thereof is engaged with a snap fastener 52 that is engaged with the ring 46. At a suitable point between the ends 50, 51 the strap 49 is provided with a second snap fastener 53, which, when the strap is worn in the manner suggested in Figure 1, is engaged with the ring 48.

From the description thus far it will be seen that to support the set in proper manner to permit use of the same without inconvenience, a portion of the strap 49 is used as a neck strap, while the remaining portion of said strap is used as a body strap. In this connection it will be noted that when the set is in use, the part of the strap between the end 51 thereof and clasp 53 is passed about the neck, and the clasp 53 applied to the ring 48. The remaining portion of the strap, that is the portion of the strap between the end 50, and the clasp 53 will extend across the back of the lineman at a point adjacent the shoulder blades. With the strap thus applied the set will be held suspended from the body in a manner to facilitate use of the same.

When all the parts are arranged in the casing 17, and the set is being transported, the same may be suspended from the shoulder of the lineman by using the strap 49 as a shoulder strap. Obviously when the strap 49 is used as a shoulder strap the clasp 53 is disengaged from the ring 48 and the strap 49 will then extend diagonally across the front and back of the lineman, and over one shoulder.

Even though I have herein shown and described the preferred embodiment of the invention, it is to be understood that the same is susceptible of further changes, modifications and improvements coming within the scope of the appended claims.

Having thus described my invention, what I claim as new is:

1. A line test set case provided with a hingedly mounted cover, a lining for the case comprising separable side and bottom mem-

bers lining the sides and bottom of the case and a cover lining arranged within the cover of said case; a partition hinged to one of the side lining members, a stop bracket on a side lining member opposite to the first named side lining member and with which the partition is engaged when in parallelism with the bottom of the case, a switch mounted on the under side of said partition, and a plunger mounted for vertical shifting movement in the first named side lining member and engageable with the switch for opening it when the cover of the case is moved to a closed position, said plunger member having one end 15 thereof disposed for engagement by the cover as the latter is moved to a closed position.

2. In a line test set, a case, a collapsible liner arranged in the case and including a hinged partition dividing the case into upper 20 and lower compartments, the lower compart-

ment being adapted to receive the following instrumentalities of the line test set, namely, batteries, transformer and magneto; and the upper of said compartments being adapted to accommodate a transmitter mounted on the hinged cover of the case together with a receiver and a clip equipped testing wire; a switch mounted on the under side of the hinged partition; a switch operating plunger mounted for vertical movement in a side member of the collapsible lining and a spring device engaged with the plunger normally urging one end thereof outwardly at the top of the case to be engaged by the cover of the case when the latter is moved to a closed position to thereby open the switch and maintain the same in the open position when the case is closed.

In testimony whereof I affix my signature.

HARVEY L. WHITLEY.
